(No Model.)

R. P. HEILMAN & R. B. PERKINS.

TRICYCLE HOBBY HORSE.

No. 325,408.

Patented Sept. 1, 1885.

UNITED STATES PATENT OFFICE

RUSSELL P. HEILMAN, OF EMPORIUM, PENNSYLVANIA, AND RICHARD B. PERKINS, OF HORNELLSVILLE, NEW YORK.

TRICYCLE HOBBY-HORSE.

SPECIFICATION forming part of Letters Patent No. 325,408, dated September 1, 1885.

Application filed May 12, 1885. (No model.)

To all whom it may concern:

Be it known that we, RUSSELL P. HEILMAN, of Emporium, in the county of Cameron and State of Pennsylvania, and RICHARD B. PERKINS, of Hornellsville, in the county of Steuben and State of New York, have invented a new and Improved Tricycle Hobby-Horse, of which the following is a full, clear, and exact description.

10 The object of our invention is to provide a new and improved hobby-horse which can be operated in the same manner as a tricycle.

The invention consists in the construction and arrangement of parts, as will be hereinafter described and claimed.

15 Reference is to be had to the accompanying drawings, forming a part of this specification, in which similar letters of reference indicate corresponding parts in all the figures.

20 Figure 1 is a side view of our improved hobby-horse. Fig. 2 is a plan view of the same. Fig. 3 is a detail end view of the front wheel. Fig. 4 is a side view of the hub of the front wheel. Fig. 5 is a detail cross-sectional 25 view of the front wheel. Fig. 6 is a side view of a fixed rear leg. Fig. 7 is a face view of the rear frame. Fig. 8 is a detail view of the top part of a modification of the rear frame.

The shaft A is arranged to turn in the hobby-horse B at the base of the neck, and has a cross-piece, B', on its upper end.

On the lower end of the shaft a fork, C, is secured, the shanks C' of which are made in imitation of the horse's front legs.

35 In the lower ends of the shanks a shaft, D, is journaled, which has a crank, E, on each end, the cranks having foot-rests E'.

Between the shanks C' a hub, F, is rigidly mounted on the shaft, and is provided with 40 radial pockets F', for receiving the wire spokes G' of the wheel G.

If desired, the hub may have radial grooves G', for receiving the ends of the wire spokes, this construction being shown in Fig. 4.

45 Rods J are pivoted to the shanks C' at the upper ends of the same, and are connected by rods H with the ends of the cranks E. The

rods J may have the shape of a horse's front legs. Rods K, having their upper ends held to the sides of the horse-body at the rear, extend downward and outward, and in their lower ends the rear axle, L, is journaled, which carries the rear wheels, M.

The rear axle, L, has two cranks, N, on which rods O are pivoted, having their upper ends connected by bars P with the sides of the horse-body, the rods P having the shape of the upper parts of horse's rear legs.

If desired, the rear legs may be of one piece, Q, without joints, as shown in Figs. 6, 7, and 8. They are united by a cross-bar, Q', and are held in place on the horse's body by pins passed through apertures in the upper ends of the bars, or by pins Q'', fixed on and projecting inward from the upper ends of the legs Q.

When the legs Q are used, the rear axle is made straight and without cranks.

The operation is as follows: The horse-body is mounted in the usual manner, and the front wheel, G, revolved by means of the cranks E on the foot-rests E', on which the feet are placed. The rods H J are moved, and in their movements resemble the moving front legs of the horse. The rear rods, P O, are moved by the cranks N of the rear axle, L, and resemble the moving rear legs of the horse.

The device is steered by turning the fork C by means of its rod A, whereby the wheel G is turned to the right or left.

Having thus fully described our invention, we claim as new and desire to secure by Letters Patent—

1. In a hobby-horse, the combination, with the horse-body B, of the steering-rod A, passed down through the body at the base of the neck, the fork C, secured to the lower end of said rod, the axle D, mounted in said fork, and provided with foot-cranks, the connected rods H J, pivoted, respectively, to the crank-axle and to the fork C, the wheel G, and the rear wheels, M, substantially as set forth, whereby the rods H J will be turned by the yoke without interfering with their action, as described.

2. A hobby-horse comprising a horse-body,

B, a steering-rod passed down through the base of the neck thereof, a fork, C, axle D, having foot-cranks E, rods H J, pivoted to the cranks and upper part of the fork and to each other to turn with the fork, the rear supporting rods, K, the crank-axle L, mounted thereon, and the pivoted rods O P, pivotally connected to the cranks of the axle and to the rear part of the horse-body, whereby the front and rear rods H J O P will be given a movement similar to the legs of a horse in motion and the forward rods allowed to turn with the fork without having their motion interrupted, substantially as set forth.

15 3. In a hobby-horse, the combination, with the horse-body, of the front driving-wheel, G, the rear axle, L, the rods K, for holding the

same, and the pivoted rods O and bars P, substantially as herein shown and described.
